UNITED STATES PATENT OFFICE.

CHARLES H. McDONALD, OF BARTLESVILLE, OKLAHOMA.

VALVE.

Application filed November 3, 1922. Serial No. 598,803.

To all whom it may concern:

Be it known that I, CHARLES H. McDONALD, a citizen of the United States, residing at Bartlesville, in the county of Washington and State of Oklahoma, have invented certain new and useful Improvements in Valves, of which the following is a specification.

This invention relates to valves, and more particularly to standing valves for oil wells.

An object of the invention is the provision of a standing valve which will fit in the bottom of the working barrel of an oil pump and which is provided with upper and lower valve members having a space between them for a body of oil to act as a seal.

A further object is the provision of a standing valve in which the lower valve member will function properly and will not be interfered with by the vacuum in the well casing or by gas contained in the oil.

In the accompanying drawings, I have shown one embodiment of the invention. In this showing:

Figure 1 is a vertical longitudinal sectional view of a well casing showing the invention applied,

Figure 2 is a similar view of the standing valve removed,

Figure 3 is a horizontal sectional view on line 3—3 of Figure 2,

Figure 4 is a similar view on line 4—4 of Figure 2, and,

Figure 5 is a similar view on line 5—5 of Figure 2.

Referring to the drawings, the reference numeral 1 designates generally a well casing having a working barrel 2 arranged therein. A standing valve 3 is adapted to be secured to the lower end of the working barrel. As shown, the exterior of the standing valve is provided with a shoulder 4 and a plurality of packing rings 5 are arranged above the shoulder. These rings are adapted to fit snugly within the lower end of the working barrel to prevent passage of fluid between the outside of the standing valve and the working barrel. The standing valve is retained in position by means of a union 6.

The upper end of the standing valve is provided with a cage 7 having the usual openings 8 to permit passage of fluid into the working barrel. A valve seat 9 is arranged in the bottom of the cage and a ball valve 10 is placed in the cage and adapted to en-

gage the valve seat. The bottom of the standing valve is provided with a portion 11 of greater diameter than the main portion and a pin 12 is arranged therein. A valve seat 13 is arranged below this pin and is adapted to receive a ball valve 14. A gas anchor 15 is secured to the lower end of the standing valve. A perforated pipe 16 may be arranged around the standing valve, the pipe being provided with openings 17 for the passage of oil.

In operation, a traveling valve of the usual character is arranged in the working barrel above the standing valve. On the up-stroke of the traveling valve, the balls 10 and 14 are lifted from their seats and the oil in the standing valve passes into the working barrel. Additional oil then flows from the well through the perforations 17 into the working barrel. On the down-stroke of the traveling valve, the balls 10 and 14 engage their seats and the oil in the working valve is prevented from flowing back into the well. This provides a body of oil in the standing valve at all times which acts to positively force the lower valve 14 to its seat and further acts to form a vacuum in the standing valve when it is drawn upwardly to positively open the lower valve. With the present types of standing valve, considerable difficulty has been encountered where a vacuum is maintained in the casing, as this vacuum has a tendency to hold the lower valve on its seat against the vacuum created within the standing valve, when the traveling valve moves upwardly. The provision of a liquid seal between the two ball valves further provides a more positively operated valve, eliminating trouble due to gas contained in the oil.

It is to be understood that the form of my invention herewith shown and described is to be taken as a preferred example of the same, and that various changes in the shape, size, and arrangement of parts may be resorted to without departing from the spirit of the invention or the scope of the subjoined claim.

Having thus described my invention, I claim:

A standing valve comprising an elongated integral body portion having a smooth cylindrical bore extending downwardly from its top throughout the greater portion of its length, the lower end of said body por-

tion having a smooth cylindrical bore of greater diameter than that in the upper end of said body portion, a valve seat arranged in said lower bore, a valve normally engaging said seat, a transverse pin extending through said lower bore above said valve to limit the upward movement thereof, a

cage arranged above said body portion, a valve seat arranged between said cage and said body portion, and a valve arranged in said cage and normally engaging said last named seat. ¹⁰

In testimony whereof, I affix my signature
CHARLES H. McDONALD.
